UNITED STATES PATENT OFFICE

JOHN B. MORGAN, OF DETROIT, MICHIGAN, ASSIGNOR OF ONE-TWENTIETH TO JOHN H. KENNEDY AND ONE-TWENTIETH TO JOHN W. HARRISON, BOTH OF DETROIT, MICHIGAN; WILLIAM HENRY GALLAGHER ADMINISTRATOR OF SAID MORGAN, DECEASED.

AUTOMATIC VALVE.

1,068,154.

Specification of Letters Patent. Patented July 22, 1913.

Application filed June 24, 1911. Serial No. 635,079.

To all whom it may concern:

Be it known that I, JOHN B. MORGAN, a citizen of the United States of America, residing at Detroit, in the county of Wayne 5 and State of Michigan, have invented certain new and useful Improvements in Automatic Valves, of which the following is a specification, reference being had therein to the accompanying drawings.

10 The invention relates to automatic valves such as are employed in connection with steam heating systems of the vacuum type, and the invention consists in the construction as hereinafter set forth.

15 In the drawings, Figure 1 is a central longitudinal section through the valve; Fig. 2 is a perspective view of the adjustable weighted lever; and Fig. 3 is a perspective view of the valve.

20 It is one of the objects of the invention to obtain a construction of automatic valve which dispenses with the use of springs, and further to provide a means of adjustment by which the operation of the valve may be 25 varied. Thus in vacuum steam systems where a number of such automatic valves are employed at different distances from the vacuum pump, it is necessary to adjust the valves nearest the pumps differently from 30 those at a greater distance.

In detail, A is the outer casing which at its upper end is provided with a removable cap B.

C is a valve seat which is detachably engaged with an apertured partition D within the casing and may be removed or inserted through the opening closed by the cap B.

35 E is a valve upon the pendent stem F which is pivotally connected at its upper end 40 to a lever G. This lever is fulcrumed at H within the casing and is provided with a weight I on the opposite side of the fulcrum from the valve and which yieldably holds the valve to its seat.

45 To provide means for varying the pressure at which the valve E will open, the weight I is adjustably secured upon the lever G, preferably by providing said weight with a slotted arm J which is secured to the 50 lever G by a clamping screw K being held in alinement by a guide lug L engaging the slot M. The arm J is also preferably provided with an upwardly extending portion N which forms an actuating member

for adjusting the weight when the screw K is released. A further range of adjustment is obtained by the provision of auxiliary weights O. These are preferably detachably secured to the weight I and as shown the weight O is provided with a stem Q having 60 a projecting portion Q' for engaging an aperture in the weight I. The end of the stem Q forms a handle by which the weight O may be engaged or disengaged.

The valve E is preferably provided with 65 a spherical bearing face which engages an annular sharpened edge or bearing U on the valve seat formed by oppositely beveled faces thereof. This forms practically a line contact, the bearing surface being so restricted that the force exerted by the valve thereagainst is more effective than with a larger surface. Furthermore, on account of the limited surface contact there is less danger of adhesion of the valve to its seat and a 70 lesser force is necessary to break this adhesion.

With valves of this type it is necessary to provide a restricted air vent or by-pass around the valve. For this purpose I have 80 provided a tubular stem V which engages an aperture W through the partition D, said stem being slotted above its point of engagement at X to form a vent aperture. This 85 vent aperture is maintained free from the lodgment of incrustation by providing an extension Y of the lever G, the end of which projects into the slot X and thus the movement of the valve toward and from its seat will cause the finger Y to travel in the slot X 90 and clear the same from any accumulation of sediment. This by-pass is therefore formed by the aperture W and the slotted stem and communicates with the casing at a point above the high level to which the 95 liquid will rise in the normal operation of the system.

The construction is such that all of the working parts of the valve may be removed or inserted through the upper end of the 100 case when the cap B is removed, and this avoids the necessity of disconnecting the valve from the system when it is necessary to make adjustment or repairs.

To permit of removing the mechanism 105 from within the valve case the stem F for the valve has a hook F' for pivotally engaging the same with a pin F² on the lever

G, and said lever is fulcrumed upon the pin H which extends through the case and is removable from outside thereof. Thus by withdrawing the pin H and unhooking the stem F all the parts of the mechanism may be withdrawn from the case when the cap B is removed.

In the operation of the parts, when the water of condensation within the casing becomes sufficient to overcome the weights O and I, the valve will lower away from its seat, which will rock the lever G, but the opening movement of the valve is limited by the projection Y engaging the upper end of the by-pass W. After the water of condensation has discharged the weights O and I will return the lever G to its normal position, yieldably drawing the valve to its seat.

20 What I claim as my invention is:

1. The combination with a case, of a lever therein, a valve actuated by said lever, a partition in said case having a port closed by said valve and an auxiliary port, a slotted stem adjustably secured in said auxiliary port to vary the restriction of the passage, and an extension of said lever engaging the slot in said stem and operating in the movement of the lever to clear said slot from obstruction.

2. The combination with a case, of a valve therein, a weighted lever pivotally connected to said valve, a partition having a port closed by said valve and an auxiliary port, a slotted stem adjustable to variably restrict said port, and a finger projecting from said lever and engaging the slot in said stem, for the purpose described.

3. The combination with a case, of a valve therein, a partition in said case having a port closed by said valve, a weighted lever fulcrumed within the case and operatively connected to the valve, said weighted lever acting normally to close the valve, and an auxiliary by-pass having the upper end

thereof positioned to engage and limit the travel of the lever in one direction.

4. The combination with a case, of an upwardly seating valve therein, a partition in said case having a port closed by said valve, a lever pivoted intermediate its ends, a pendent stem for attaching the valve to the lever secured to the latter upon one side of the lever pivot, a weight acting on the lever upon the opposite side of said pivot to yieldably draw the valve to its seat, said lever having a portion projecting beyond the point of engagement of the stem therewith, and an auxiliary by-pass having the upper end thereof positioned to engage said extension and limit the travel of the lever in the opening movement of the valve.

5. The combination with a case, of an upwardly seating valve therein, a partition in said case having a port closed by said valve, a lever pivoted intermediate its ends, a pendent stem for attaching the valve to the lever secured to the latter upon one side of the lever pivot, a weight acting on the lever upon the opposite side of said pivot to yieldably draw the valve to its seat, said lever having a portion projecting beyond the point of engagement of the stem therewith, and means upon the casing for engaging said lever projection in the opening movement of the valve, for the purpose described.

6. The combination with a case, of a valve therein, a pivoted counter-weighted lever connected to said valve, a partition having a port closed by said valve, a slotted by-pass, and a finger projecting from said lever and positioned within said slot, for the purpose described.

In testimony whereof I affix my signature in presence of two witnesses.

JOHN B. MORGAN.
